[57] CLAIM

The ornamental design for a room heat recirculator, substantially as shown and described.

DESCRIPTION

FIG. 1 is an elevational view of a room heat recirculator showing my new design,

FIG. 2 is a top plan view thereof, the bottom being the same as the top shown;

FIG. 3 is an enlarged cross sectional view taken on line 3—3 of FIG. 1; and

FIG. 4 is an enlarged fragmentary cross sectional view taken on line 4—4 of FIG. 1.

FIG. 2.

FIG. 3.

FIG. 4.
